APPARATUS FOR RECLAIMING
CRANK-CASE OILCharles P. Shillaber, New York, N. Y., assignor
to Quigley Company, Inc., a corporation of New
York

Application March 24, 1933, Serial No. 662,427

6 Claims. (Cl. 196—16)

This invention relates generally to the fractional distillation and separation of the constituents of mixed hydrocarbon liquids, and the elimination of solid contained impurities therefrom, but is more specifically designed for use in the reclamation of crank case oils, and the purification of other mineral oils.

The lubricating oil put in the crank cases of internal combustion engines used on motor cars, and forced through the bearings and into the cylinders of such engines, soon becomes diluted with gasoline and water and loaded with carbon and other solid impurities to a point that renders it useless and injurious to the engine, so that it has to be removed and replaced with fresh oil. The lubricating oil contained in such mixture is, however, as useful as ever, if it can be separated from the other and objectionable constituents thereof.

Various types of processes and of apparatus have heretofore been proposed for separating out these impurities and adulterants from the basic constituent, the lubricating oil which still constitutes the bulk of the liquid taken out of the crank case, but none of these has heretofore been found sufficiently safe, efficient and economical in operation to render it an unqualified commercial success. The present invention, however, affords a satisfactory solution of the problem.

To that end the main objects of my invention are to perfect a simple distilling apparatus which may be operated at relatively high speed without danger of explosion, requires in its construction only standard materials which may be purchased cheaply in the open market, recovers a high percentage of the lubricating oil contained in the waste product taken from crank cases, and utilizes the more volatile impurities therein as fuel for carrying on the distillation process.

The best form of apparatus at present known to me embodying my invention is illustrated in the accompanying two sheets of drawings, in which:

Fig. 1 is a diagrammatic side elevation of a plant embodying my invention, with parts broken away and others shown in section.

Fig. 2 is a vertical, approximately central partial section of the still on a larger scale, other parts being shown in elevation.

Fig. 3 is a detail plan view of the same, parts being omitted and others shown in section on line 3—3 of Fig. 2.

Fig. 4 is an enlarged detail vertical section on

line 4—4 of Fig. 2, showing the steam jet ports.

Throughout the drawings like reference characters indicate like parts. Referring to Fig. 1, a furnace shell of any suitable form is indicated at 1 in which is set the container 2, preferably of horizontal circular interior cross section with a downwardly dished bottom, though any convenient form of liquid container may be employed. As shown, this container is surrounded at its top edge by a circular angle-iron flange 43, portions of which rest on the slightly curved I-beams 40, 40, supported on the furnace casing. The latter has an upper, slightly overhanging portion closely surrounding the upper portion of the container 2, but leaving an annular space 42 below it through which the gases of combustion may circulate produced by the combustion of vaporized oil discharged from any suitable burner 3 below the said receptacle. Liquid hydrocarbon is supplied to said burner by the pump 4 drawing from the sump 5, to which latter the liquid is delivered through pipe 6 from tank 7. A valve for controlling the flow through pipe 6 is shown at 60.

A pipe 8 controlled by valve 9 may serve for delivering the crank-case mixture to the interior of container 2 through an opening in the top plate 41. A conduit 10 connected to another opening in the top plate 41 and controlled by valve 11 is provided for carrying off hydrocarbon vapors generated in the receptacle 2 and conducting them to a condenser 12, of any desired construction, to which latter cooling water is supplied by pump 13, being discharged from the condenser through the outlet pipe 14. A pipe 15 conducts the condensed hydrocarbon liquids to the tank 7. An outlet 16 from the upper portion of tank 7 is provided through which vapors may be drawn by a suction fan and discharged into the atmosphere through a pipe 17. 40 44 is a pipe through which additional liquid hydrocarbon may be supplied to tank 7 if necessary.

18 is a drawoff conduit for the container 2 having a downwardly projecting intake end 28 which reaches nearly to the lowest portion of the bottom of said container, and 20 is a shut-off valve for said conduit, preferably located in an upwardly bowed gooseneck 19, the outer end of which extends downward to a cooling apparatus 21 of any suitable construction located somewhat below the level of the intake end 28 of the drawoff conduit. 22 is an outlet from cooling apparatus 21 through which the cooled oil drawn from the bottom of the receptacle 2 55

is forced by rotary pump 23 to and through the filter apparatus 24, from which latter the filtered oil may be discharged by pipe 25 to any suitable storage tank, not shown.

5 26 represents a steam pipe controlled by a valve 27, said pipe extending down to a point near the bottom 2 of said receptacle, as best shown in Figs. 2 and 4, and there having a plurality of radially extending branch nozzle pipes 10 29, 29, extending parallel and adjacent to said receptacle bottom, each of said branches being provided with a plurality of ports 30, 30, arranged to discharge steam downward at an angle of about 45 degrees against the receptacle bottom, as best shown by the arrows in Fig. 4. The ports in each radial nozzle pipe discharge in the same general direction as do those in the adjacent nozzles, so that the jets of steam issuing therefrom will all tend to produce a rotary scouring movement of the contained liquid in a counterclockwise direction around the bottom of the container 2, when one looks downward into said container.

15 31 represents a foam outlet pipe connected to an opening in the top plate 41 of the container 2. This is controlled by a valve 32 and preferably has an upper, greatly elongated portion 33 of larger internal cross section which may be shut off by valve 52. 34 is any suitable cap placed over, and spaced away from, the upper end of the foam tower formed by the conduit sections 31 and 33 so as to leave the upper end of such foam tower open to the atmosphere. 35 is a laterally extending foam takeoff preferably connected to the lower section 31 of the foam tower, above the valve 32 but below the upper valve 52, and discharging into the open tank 36, the bottom of which is above the liquid level in the container 2 and is connected by conduit 37 to the interior of said container just above said normal liquid level, which latter is indicated by the broken line 45—45 in Fig. 1 and shown in full lines in Fig. 2.

20 38 is a circular handhole in the cover 41 through which dry, activated clay may be introduced into the interior of receptacle 2. A larger handhole 39 is also provided in said cover for clean-out and other purposes.

25 In the usual method of operation about 500 gallons of crank-case waste mixture or other dirty oil is introduced into the receptacle 2 through pipe 8, the steam valve 27 being closed. Valves 9 and 11 are then closed and the burner 3 started in operation. In about an hour's time, after starting with a cold still, the temperature of the mixture in the container 2 will have risen to about 220 to 275° F. and foam will begin to rise in the stack 33 and flow out through conduit 35 into open tank 36. Such foam will evaporate in part gradually when thus exposed to the atmosphere, while the heavier constituents thereof, including the lubricating oil, will condense and flow back into container 2 for further treatment.

30 65 Heating is continued for a second hour at the expiration of which the temperature will have risen to about 350° F. The foam, which results from the presence of water, grease and other solid matter in the original mixture, will usually have stopped forming by the time the temperature has reached 300° F., at which point valve 32 is shut, valve 27 is opened, and steam at 50 lbs. pressure discharged into the bottom of container 2 through ports 30, 30. The steam so admitted violently agitates the liquid mixture

through which it passes and gives it a whirling motion. The steam helps to vaporize the volatile constituents of said mixture and to drive them out of the remaining liquid body. The fan is then started running and the valve 11 opened. This sucks the hydrocarbon vapors collected in the top of the container 2 out through pipe 10 to condenser 12 where they are reduced to liquid form and as such collect in tank 7.

10 Further heating for a third hour will raise the temperature to about 450° F. and vaporize even the heavier hydrocarbons in the original charge. These heavier vapors then collecting in the upper portion of the container 2 may be drawn out by opening valve 32 so that air will flow in and mix with them to form a lighter gaseous body which can be sucked out through conduit 10 to condenser 12 by the fan, as above described. Usually the air enters in a relatively rapid stream through the foam tower connection 31, or conduit 37, or at some other point remote from the outlet pipe 10. The gasoline and other combustible liquids so obtained, and collecting in tank 7, may be transferred later to the sump 5 for use in burner 3.

15 About ten per cent. by weight of dry, activated, clay is then added through manhole 8 and treatment by heat and steam is continued for about half an hour, as a fourth stage of the operations.

20 30 The liquid remaining in receptacle 2 is tested from time to time as the operation advances to determine its flash point and specific gravity, and when these have been brought to the normal, for the type of lubricating oil forming the valuable constituents of the original mixture, the operation is stopped, the steam and fuel cut off, the valve 20 opened, and the pump 23 started to gradually draw off the reclaimed oil from receptacle 2, through cooler 21, and force it through filter 24 to free it from the activated clay and any other solid impurities remaining in it. The cycle of operations above described requires about four hours for its completion.

25 40 As soon as the container 2 is empty, a second charge of crank case mixture is run in and the above described procedure repeated. The heat of the container in this and in succeeding operations cuts down the first stage, or warming-up step, from an hour to about 45 minutes in duration.

30 45 The function of the clay is to adsorb the carbon and other solid impurities existing in the original crank-case mixture or other dirty oil mixture, in the well known way, and thus enable such solid impurities to be more easily and certainly filtered out while adhering to the larger clay particles.

40 45 The foam tower and/or foam take-off 35 permit the distillation of the mixture to be carried on at a relatively rapid rate under a high temperature without the foam blowing off or running over onto the exterior of the furnace and so carrying with it a considerable portion of the lubricating oil. On the contrary, the water content of the foam is evaporated, or partly condensed, and its contained oil and gasoline are returned to the still for further treatment. Also the outlet provided by the foam tower permits a high temperature to be applied to the liquid without generating a high internal vapor pressure in the receptacle, such as would occur if some such vapor outlet were not provided, such high internal pressure being dangerous, and also

retarding the vaporization of the contained gasoline and water in the original mixture.

If for economy in first cost or other reason it is desirable to dispense with the upper portion 33 of the foam tower it may be cut off and valve 52 closed. This will force all the foam into tank 36, where it will either vaporize or condense if the area exposed to the atmosphere is large enough to handle the full supply.

10 The downwardly turned end 28 of the draw-off conduit 18 and the elevated position of the valve 20 serve to pocket a quantity of air in conduit 18, when the still is recharged, as the valve 20 should be closed before each charge of liquid 15 is introduced to container 2. This protecting cushion of air prevents the heated mixture in the still from reaching valve 20 during the distilling operation and thereby gumming the same up so that it would become difficult to open or 20 close.

Various changes in details of construction can be made without changing the principles of operation above described, or departing from the underlying novelty of the invention, as defined in the appended claims.

25 Having described my invention, I claim:

1. In a still for reclaiming crank-case oils having a partly closed container for the crank case mixture and means for heating the same, the combination, with said above described apparatus, of a foam collecting tower having its upper end open to the atmosphere, its lower end connected to the upper portion of the interior of said container, a discharge spout connected 30 at an intermediate point in said tower means disposed adjacent said discharge spout for returning to said container certain of the liquid constituents of the foam forced out through said

discharge spout, and valves disposed in said foam collecting tower both above and below said spout for controlling the proportions of the foam discharged through the upper end of said tower and through said discharge spout.

2. A combination such as defined in claim 1 in which the discharge spout projects laterally from said foam collecting tower, an open receptacle beneath the discharge end of said spout but above the level of the liquid in said container, 10 and a drain conduit for said receptacle discharging into said container.

3. A combination such as defined in claim 1 in which said discharge spout projects laterally from said foam collecting tower, an open receptacle beneath the discharge end of said spout but above the level of the liquid in said container for effecting a discharge from the end of said discharge spout into said receptacle through the atmosphere, and a drain conduit for said 15 receptacle discharging into said container just above the said level of the liquid in said container.

4. A combination such as defined in claim 1 in which the upper portion of said tower is of 20 relatively larger interior cross section than is the lower portion thereof.

5. A combination such as defined in claim 1 in which the portion of said tower above said discharge spout is of considerably larger interior 30 cross section than is the remaining lower portion thereof.

6. An apparatus such as defined in claim 1 combined with a protecting cap located above, and spaced away from, the upper, open end of 35 said foam collecting tower.

CHARLES P. SHILLABER.
